CLAIM

The ornamental design for a waffle maker, as shown and described.

DESCRIPTION

FIG. 1 is a perspective view of a waffle maker showing a new design;

FIG. 2 is a front elevational view thereof;

FIG. 3 is a rear elevational view thereof;

FIG. 4 is a left side elevational view thereof;

FIG. 5 is right side elevational view thereof;

FIG. 6 is a top plan view thereof;

FIG. 7 is a bottom plan view thereof;

FIG. 8 is another perspective view thereof, in a horizontal orientation;

FIG. 9 is a front view thereof, in a horizontal orientation;

FIG. 10 is a rear elevational view thereof, in a horizontal orientation;

FIG. 11 is a left side elevational view thereof, in a horizontal orientation;

FIG. 12 is a right side elevational view thereof, in a horizontal orientation;

FIG. 13 is top plan view thereof, in a horizontal orientation; and,

FIG. 14 is a bottom plan view thereof, in a horizontal orientation.

The broken lines are for illustrative purposes only and form no part of the claimed design.

1 Claim, 9 Drawing Sheets
